Primary Examiner — Catherine S Posthauer(74) Attorney, Agent, or Firm — Mei & Mark LLP(57) CLAIM

The ornamental design for a cap, as shown and described.

DESCRIPTION

FIG. 1 is a side view of a cap showing a first embodiment of my new design;

FIG. 2 is a top view thereof;

FIG. 3 is a top perspective view thereof;

FIG. 4 is a bottom perspective view thereof; and

FIG. 5 is a bottom view thereof.

FIG. 6 is a side view of a cap showing a second embodiment of my new design;

FIG. 7 is a top view thereof;

FIG. 8 is a top perspective view thereof;

FIG. 9 is a bottom perspective view thereof; and,

FIG. 10 is a bottom view thereof.

The evenly broken lines are shown for the purpose of illustrating parts of the article that form no part of the claimed design. The dot-dash lines represent the boundaries of the claim and form no part thereof.

1 Claim, 10 Drawing Sheets(56)
